(57) **CLAIM**

The ornamental design for a round surface mounted LED light fixture, substantially as shown and described.

DESCRIPTION

FIG. 1 is a bottom perspective view of an embodiment of the new design;

FIG. 2 is a top perspective view of the embodiment of FIG. 1;

FIG. 3 is a bottom view of the embodiment of FIG. 1;

FIG. 4 is a top view of the embodiment of FIG. 1;

FIG. 5 is a left side view of the embodiment of FIG. 1;

FIG. 6 is a right side view of the embodiment of FIG. 1;

FIG. 7 is a front view of the embodiment of FIG. 1; and,

FIG. 8 is a back view of the embodiment of FIG. 1.

The design consists of the features of shape, ornament and configuration of the article shown in the drawings. The broken lines shown in the drawings are for the purpose of illustrating portions of the article that form no part of the claimed design.
